UNITED STATES PATENT OFFICE.

EDWIN MARION ARNOLD, OF TULSA, OKLAHOMA.

LUGGAGE-CARRIER FOR AUTOMOBILES.

1,233,162.

Specification of Letters Patent. Patented July 10, 1917.

Application filed October 18, 1916. Serial No. 126,277.

To all whom it may concern:

Be it known that I, EDWIN M. ARNOLD, a citizen of the United States, and a resident of Tulsa, in the county of Tulsa and State 5 of Oklahoma, have invented a new and Improved Luggage-Carrier for Automobiles, of which the following is a full, clear, and exact description.

My invention relates to means for carrying trunks and luggage on an automobile, and has for its general object to provide a carrier applicable to the running board of the machine.

The invention also has for its object to 15 provide a carrier having means to enlarge or contract the same longitudinally or transversely, to vary its capacity.

A further object of the invention is to provide means on the carrier whereby the 20 trunk or luggage may be firmly strapped in place and be prevented from shifting or moving on the running board to scratch or mar the latter or whereby the trunk may be quickly released for removal from the carrier.

The invention furthermore has for its object to provide novel clamping means for securing the carrier in position on the running board, or effecting its ready detachment 30 therefrom.

The nature of the invention, and the advantages of the preferred structural embodiment, will more clearly appear as the description proceeds.

Reference is to be had to the accompanying drawings forming a part of this specification in which similar reference characters indicate corresponding parts in all the views.

Figure 1 is a perspective view of a luggage carrier embodying my invention, showing the same applied;

Fig. 2 is an end elevation of the carrier, the running board to which it is applied being in section;

Fig. 3 is a fragmentary plan view;

Fig. 4 is a front view with parts in section on the line 4-4, Fig. 2;

Fig. 5 is a detail end view of the clamp 50 members modified to conform to a running board having no depending flange or apron.

In carrying out my invention in accordance with the illustrated example, the carrier is formed with end structures and an 55 adjustable front. Each end structure includes a lower clamp arm 10 adapted to be

disposed transversely beneath the running board B of an automobile A, and may be provided at its inner end with a set screw 11 to bear against the under side of the running board. In the form shown in Figs. 1 to 4 the outer end of clamp arm 10 is formed with a depending member having a vertical slot 12 to receive the downturned flange b of the running board.

The clamp arm 10 is integral or otherwise rigid with uprights 13 rising at a height to extend above the running board. On each post 13, near the lower end, a clamp arm 14 is pivoted at its outer end as at 15 to swing in a vertical plane from the lowered clamping position indicated in full lines Fig. 2 to a raised position as in dotted lines. To secure each upper clamp arm 14, a locking post 16 is pivoted at its upper end by a 75 bolt 18 or the like to the inner end of an upper transverse bar 20, the respective bars 20 being rigid respectively at their outer ends with the adjacent posts 13. Thus, the posts 16 may swing in vertical planes on the 80 bolts 18. At the lower end, each post 16 is vertically slotted as at 17 to snugly receive the adjacent clamp arm 14 and is threaded to receive a clamping nut 17^a so that the tightening or loosening of the said nut will 85 cause the slotted end of the post to tightly bind, or release, the arm 14.

In Fig. 5, the clamp is adapted for a running board, B', having no depending flange or apron at the outer edge. In this form the 90 post, 13^a, rises directly from the bottom clamp arm 10^a, there being no need for the slot 12 of the first form. The set screw 11, upper clamp 14, and the locking post 16 with its nut 17^a, are the same as previously 95 described.

To strap a trunk C or the like in position on the running board within the carrier, I provide a trunk strap 19 adjustable by the usual buckle. The ends of the strap 19 are 100 secured to loops 21 provided on the cross bars 20 at the inner ends thereof.

Thus with the carrier in position the trunk may be firmly secured against movement and thereby prevented from scratching or 105 otherwise marring the running board.

A front is provided on the carrier connecting the end structures thereof and adapted to be extended or contracted or adjusted transversely on the end structures. For the 110 stated purpose slide bars 22 are provided with keepers or slides 23 at the inner ends

thereof embracing the rigid bars 20 and provided with set screws 24. The bars 22 have also guided movement in rigid keepers 25 on the upper ends of the uprights 13, and 5 provided with set screws 26 at the outer ends. The slide bars 22 carry posts 27 that extend above and below the same. The respective posts 27 are extensibly connected, use being made for this purpose of a lazy tongs 28. 10 The end members of the lazy tongs 28 are pivotally secured at the bottom to the posts 27 by fixed bands 29 on said posts, or equivalent means, while at the top the end members are pivotally connected with sliding 15 bands or sleeves 30 on said posts. Set screws 31, 32 may be provided on the bands 29, 30. Stop pins 33 may be provided on the posts 27 to prevent complete displacement of the bands 30. 20 It will be obvious that through the medium of the lazy tongs 28 the carrier may be collapsed endwise or extended to accommodate baggage of a given size or quantity and the front may be adjusted transversely 25 through the medium of the slide bars 22. In securing the carrier in position with the form of clamp shown in Figs. 1 to 4, the nuts 17^a are raised and posts 16 swung on the bolts 18, and the upper clamp bars 14 are 30 swung upwardly on their pivots 15 to whatever extent may be necessary to permit the lower clamp members 10 to be passed beneath the running board and engaged with the flange *b* thereof. The upper clamp bars 35 14 are then lowered to clamping engagement with the top of the running board and the posts 16 secured in the locking position. In removing the carrier, the raising of the clamp members 14 will permit the lower 40 clamp members to drop out of engagement with the running board. With the form shown in Fig. 5, the release of the locking posts 16 and set screws 11 permit of the clamps being passed onto or removed from 45 the running board by straight sliding move-

ments without a dropping movement of the lower clamp arm 10. When not in use the carrier, it will be evident, may be collapsed into small compass and conveniently carried in the tool box. 50

Having thus described my invention I claim as new, and desire to secure by Letters Patent:

1. A luggage carrier of the class described including end structures and a front connecting said end structures, each end structure comprising a clamp member adapted to be disposed transversely beneath the running board of an automobile, an upper clamp member pivoted to swing in a vertical plane 60 above the running board, transverse members on the end structures above the upper clamp members, and a swinging locking device pivotally hung on each of said transverse members and each having means at its 65 lower end engageable with the upper clamp arm to lock the same. 55

2. In a luggage carrier of the class described, end structures each including a frame, a lower clamp member rigid with the 70 frame at the bottom and adapted to be disposed beneath the running board of the automobile, an upper clamp member pivoted on said frame to swing in a vertical plane to effect clamping engagement with the running board at the upper side, a front connecting the said end structures, the end frames having rearwardly extending members above the upper clamps, depending locking devices pivotally hung on said members 75 to swing toward or from the said upper clamp members, and means adjustable on said locking devices to effect engagement with or to disengage the upper clamp members. 80
